G. Smith, H. Brown & J. A. Read of Philadelphia, Pa.
Assignors to J. G. Abbott & Archibald Lawrence of the same place.

Letters Patent No. 805, Dated June 17th 1856.

The schedule referred to in these Letters Patent, and making part of
the same.

To all whom it may concern:

Be it known that we, Garretson Smith,

Henry Brown, & Joseph A. Read of the City and County of Philadelphia, and State of Pennsylvania, have produced a new and original Stove design, designated as Stove "A good Egg"; and we do hereby declare that the following is a full, clear, and exact description of said design, reference being had to the annexed drawings, forming part of this specification, in which,

Figure 1, is a side elevation of the stove

Figure 2, is a top view of base plate.

Figure 3, is a front view of foot of stove

Figure 4, is a plan of stove base corner

Figure 5, is an elevation of ash pit door.

The body of the stove rests on a base similar to that of a common stove. It has an egg form as shown in figure 1. Around its middle is a projecting rim, of waving form, ornamented with projections b. Above the rim are the scale like ornaments c; and below the rim are the ornaments made up of figures e, f and g; the arrangement and configuration being as shown in the drawing. Above the swell of the stove, there are a series of mouldings h, i, j and k, resembling a capital of a column. The moulding h, is ornamented by projections l, and moulding k, by figures m, in bas-relief; the configuration of these several ornaments and mouldings being as in fig 1. Below the egg there is an ogee moulding n.

The base B, is of square cross section with rounded corners which are ornamented with reeds p. The base is further embellished with figures r and s, arranged and configured as set forth in the drawing. The corners of base B, have an ornament t, composed of foliage as is shown in figure 4.

The base plate C, is of the form shown in fig 2, and has its edge ornamented with foliage u, wavy ornament v, and projections w, arranged and having the configuration shown in figure 2.

The foot F, is embellished with figures a and b, foliage c', and paw d', the arrangement and configuration being as shown

Des 805

in figure 3.

The ash pit cover R, is ornamented as base sides, and bears the inscription "A good egg" in raised capitals.

The base plate bears the inscription "Abbott & Lawrence, Philadelphia, patented 1856," in raised capitals and numerals.

We claim the design, configuration and arrangement of the plates, and the ornaments thereon, as set forth, and delineated in the drawings.

In testimony whereof, we have hereunto signed our names before two subscribing witnesses.
